UNITED STATES PATENT OFFICE.

GEORGES MISSOGENIS, OF EDGEWATER, NEW JERSEY, ASSIGNOR, BY MESNE ASSIGNMENTS, TO PLATO GUIMES, OF PALISADE, NEW JERSEY.

FOLDABLE COT.

1,392,195.

Specification of Letters Patent. Patented Sept. 27, 1921.

Application filed August 6, 1918, Serial No. 248,543. Renewed August 24, 1921. Serial No. 494,922.

To all whom it may concern:

Be it known that I, GEORGES MISSOGENIS, a subject of the King of Greece, residing at Edgewater, county of Bergen, State of New Jersey, have made a certain new and useful Invention in Foldable Cots, of which the following is a specification.

This invention relates to foldable cots or beds.

10 The object of the invention is to provide a cot or bed structure which is simple, economical to manufacture, efficient in operation, and which is capable of being folded into a light compact package of small dimensions and small weight or distended into position to form a cot or bed.

15 A further object of the invention is to provide a foldable cot of the nature referred to which is strong and durable, and which affords comfortable resiliency when in use.

20 A further object of the invention is to provide a foldable cot of the nature referred to with a convenient head rest.

25 Other objects of the invention will appear more fully hereinafter.

30 The invention consists substantially in the construction, combination, location and relative arrangement of parts, all as will be more fully hereinafter set forth, as shown in the accompanying drawing, and finally pointed out in the appended claim.

In the drawings:

35 Figure 1 is a view in side elevation of the frame for a foldable cot or bed constructed in accordance with and embodying the principles of my invention, and showing the frame in distended position for use.

40 Fig. 2 is a top plan view of the construction shown in Fig. 1.

45 Fig. 3 is a view in vertical transverse section on the line 3; 3, Fig. 1, looking in the direction of the arrows.

Fig. 4 is a broken detail view in section of the construction at the foot of a supporting leg.

50 Fig. 5 is a broken detail view showing the foldable connections of the brace rods employed.

55 Fig. 6 is a broken detail view in top plan, parts in horizontal section, showing the side tensioning members.

Fig. 7 is a broken detail view on the line 7; 7, Fig. 1, looking in the direction of the arrows, and showing the swivel plate connection of the legs and top or mattress sup-

porting arms to the main body member of the frame.

Fig. 8 is a broken detail view in section on the line 8; 8, Fig. 7, looking in the direction of the arrows.

Fig. 9 is a broken detail view in elevation of the reverse side or face of the swivel connection shown in Figs. 7 and 8.

Fig. 10 is a broken detail view showing the connection of a side member of the mattress support to a supporting arm therefor.

Fig. 11 is a broken detail view showing the connection of a part forming a portion of the head rest structure.

The same part is designated by the same reference numeral wherever the same occurs throughout the several views.

The main body portion of the cot frame consists of the members 12, 13, preferably formed of metal and of channel formation,

as clearly shown in Figs. 3, 7 and 8. These main body members are hinged together at their abutting ends upon the hinge pivot

14 so as to fold upon each other when the frame is to be folded up or distended into

line with each other for use as a cot or bed as shown in Figs. 1 and 2. Suitably hinged upon the pivot bolt 14 of the main body members 12, 13, and depending therefrom when the frame is distended for use,

but foldable against the body members when the frame is folded up, is a bracket 15, to the lower end of which is connected a brace plate 16 to which are anchored the brace rods 17, 18. Also suitably pivoted upon the body members 12, 13, at their hinge axis

upon a pivot bolt 19 is a plate 20, to ears on which are pivotally connected as at 21

brace arms 22 which extend transversely across the frame when distended for use to brace the side members 23 of the mattress support.

It will be observed that the brace plate 20 extends transversely across the main body members 12, 13. The brace plate 16, however, extends in the direction of the

extended length of the body members, and at the opposite edges thereof is provided with hook portions 24 over which the leg braces 18 engage, and with eyelets into

which the braces 17 engage. At the remote ends of the body members 12, 13, are pivotally secured swivel members 25, which project outwardly or away from the ends of the body members 12, 13, and each of which

is provided with ears 26 forming sockets

110

within which are pivoted the ends of leg members 27 and top supporting arms 28 in equally spaced relation to each other. The leg members 27 when the frame is distended 5 for use extend outwardly and downwardly away from each other to constitute supporting legs for the cot. In practice I prefer to form the leg and arm members 27 28, of metal tubes to reduce weight and to 10 the free ends of the leg members 27 are suitably secured caps 29 to afford means for attachment thereto of the brace members or rods. A simple method of attaching the caps 29 to the free ends of the legs is shown 15 in Fig. 4 wherein the free ends of the tubular legs are rounded over as indicated at 30 to form a retaining shoulder for an interior washer 31. A cap 29 is applied to or over the free end of the tubular leg 27 20 and is riveted as at 32 to the interior washer 31. When the frame is in distended position for use the caps 29 at the free ends of the legs 27 at the same end of the frame are connected together by brace rods 33. 25 Said caps are also connected through brace rods 34 to the free ends of the top supporting arms 28. The leg braces 18 above referred to which are connected at one end to the brace plate 16 as above described are 30 also connected at their opposite ends to the caps 29. In practice I prefer to make the various braces 17, 18, 33 and 34 in pivotally connected sections so as to permit them to be readily and easily folded together. In 35 the case of the leg braces 18 a single member is connected to the hook portion 24 of the brace plate 16 while independent portions connect the opposite end of said single portion respectively to the caps 29 of the 40 two opposite legs 27 at the same end of the same, as most clearly shown in Figs. 2 and 3. A simple form of hinge connection between the portions of the various braces is shown wherein in the case of the leg braces 45 18, for example, see Fig. 5, the single portion which is connected to the brace plate 16 has the end thereof bent or doubled back upon itself to form an eyelet 35, and held in place by means of a clip or sleeve 36, the 50 extremity 37 of said end portion being bent over the end of the sleeve 36. Through the eye 35 is passed similar eyes similarly formed in the ends of the other portions of the braces 18. In like manner the portions of the brace or tie rods 34 are connected together. See particularly Figs. 1, 2 and 3. This affords an exceedingly simple form of connection which is sufficiently rigid when the parts are distended for use 55 but which permits the parts of the ties or braces to be folded together in the collapsed condition of the frame. In practice the distension between the free ends of the corresponding legs 27 at opposite ends of the 60 main frame is somewhat greater than the

combined lengths of the main body members 12, 13, thereby securing stability in the frame when distended for use, and constituting the ties or braces 17, 18, 33, and 34, in effect trusses to take the strains and 70 stresses imposed upon the frame when in use, while affording a desirable resiliency to render the bed comfortable for occupation and use.

The side wires 23 of the mattress support 75 have hooks 39 pivotally connected thereto at one end thereof which are hooked into eyelets formed in plates 40 carried by the supporting ends 28 at one end of the frame while at their opposite ends is pivotally connected a clamp member 41. This clamp member is provided with a curved arm 42, see Fig. 10, which engages through a link 43 and is retained in engaging relation by a ring 44 carried by the side wire or member 80 23. By simply slipping the ring 44 toward the left from the position shown in Figs. 1 and 10 the arm 42 is released and may be readily withdrawn from the loop or link 43, thereby detaching the mattress side supporting member 23. The link 43 is engaged into a plate 45 which is secured to the extremity or free end of the top supporting arm 28. The plate 45 may be secured to the tubular end of the arm 28 in identically the 90 same manner in which the cap 29 is secured to the free end of the leg 27 as shown in Fig. 4. The plates 45 at opposite sides of the frame are connected together by a tie rod 46, see right hand end of Fig. 2, which 100 tie rod is made in sections swivelly connected together by engaging eyes 35 exactly as above described with reference to the sectional leg ties 18. The vertical tie rods 34 are also connected into the plates 45. As 105 in the case of the legs 27 the distance between the free ends of arms 28 on the same side of the bed or other frame are a greater distance apart than the combined distended lengths of the main body frame members 12, 110 13, and hence the tie rods 34 and 46 and the side members 23 of the mattress support form in effect trusses to take the strains while securing a desirable degree of flexibility and comfort when the bed is in use 115 and at the same time permitting parts to be detached and folded together into compact relation. In like manner to the plates 45 the plates 40 at the opposite end of the frame are connected to the caps 29 at the free ends 120 of the leg members at that end of the frame through the tie rods 34, and the plates 40 at opposite sides of the frame are connected or braced together by the tie rods 47 which in like manner to the tie rods 34 are made 125 in sections pivotally connected together through engaging eyelets 35 as above explained.

At the head end of the frame I provide a foldable head rest of extremely simple con- 130

struction consisting of vertical tubular supports 48, see Figs. 1, 3 and 11. These supports are pivotally connected to clips 49 carried by horizontally disposed head rest 5 side members 50. At their extreme outer ends the horizontal members 50 are connected together by a cross member 51 which is hinged as at 52 to one of the horizontal side members 50 and detachably engaged by 10 means of a hook end 53 in the outer end of the opposite horizontal side member 50, see Fig. 2. The opposite ends of the horizontal members 50 are detachably connected by short rods 54 to the vertical tubular supports 48. The lower ends of the vertical supports 48 are provided with longitudinally extending slots 55 through which pass the vertical tie rods 34. This structure affords a very simple and efficient and at the 20 same time a foldable or collapsible and resilient comfortable head rest for the cot or bed when in distended position for use.

It is desirable to apply a suitable yielding transverse tension to the side members 23 25 of the mattress support, and for this purpose the transversely extending brace arms 22 are employed. To the outer or free ends of these brace arms 22 are pivotally connected vertically disposed members 56 having outwardly presenting hook portions 57 at their upper ends which engage the side members 23 of the mattress support. To the lower ends of the hook members 56 are pivotally connected transversely extending rods 35 57, the inner ends of which carry suitable plates 58, see Fig. 6. A tension spring 59 is interposed between the stop plate 58 and a relatively fixed plate 60 carried by the ends of a link 61 which is connected to the 40 associated brace arm 22 adjacent to the point of pivotal connection with the plate 20. The stop plate 58 slides freely along the legs of the link 61 and the spring 59 pressing thereagainst exerts its tension upon the said stop plate 58 and arm 57 and hook member 56 45 in a direction to rock the hook end 57 outwardly thus imposing a desirable yielding tension upon the side members 23 of the mattress support.

50 It is to be understood that a strong canvas, not shown, is applied over the head rest and over the side members 23, said canvas to be applied along its side edges to the side members 23, and at its ends over the tie rods 46,

47, which in addition to their tie rod function constitute the transverse end wires of the mattress support.

A cot or bed frame constructed as above described is exceedingly simple, can be compactly folded into a space a little more than 55 a foot and a half long, a little more than a half a foot wide, and a little more than a quarter of a foot high, with a total weight of approximately ten pounds, thereby rendering the same exceedingly desirable and 60 useful not only as a foldable cot or bed easily transportable, but which is strong and durable and which can be quickly distended for use or folded for transportation, and which is clean and sanitary. The structure 65 is sturdy and simple and not easily deranged and nothing to get out of order. By reason of its extreme lightness and mobility it is particularly useful and desirable for camping purposes, for army uses, for use in hospitals, particularly camp or field hospitals, 70 as stretchers for the wounded, and for many other purposes and uses.

It will be observed that the main body members constitute with the legs and top 80 supporting arms the main parts of the frame, and these members being made of light metal are not only strong and durable but capable of being easily manufactured and quickly assembled, and the completed article capable 85 of being quickly and easily folded for transportation or distended for use.

Having now set forth the objects and nature of my invention, and a construction embodying the principles thereof, what I 90 claim as new and useful and of my own invention, and desire to secure by Letters Patent, is:—

In a foldable cot or bed structure, a foldable head rest frame including vertically 95 disposed arms, and means for supporting the same, horizontally disposed members pivotally connected to said vertical arms, rods detachably connecting one end of said horizontal members to said vertical arms, and 100 a rod pivotally connected to the free end of one of said members and having detachable connection with the free end of the other of said members.

In testimony whereof I have hereunto set 105 my hand on this 30th day of July, A. D. 1918.

GEORGES MISSOGENIS.
